UNITED STATES PATENT OFFICE.

CLIFFORD C. BRADBURY, OF ROCHESTER, NEW YORK, ASSIGNOR, BY MESNE ASSIGNMENTS, TO WESTERN ELECTRIC COMPANY, INCORPORATED, A CORPORATION OF NEW YORK.

TELEPHONE SYSTEM.

1,377,555.

Specification of Letters Patent. Patented May 10, 1921.

Application filed May 16, 1910. Serial No. 561,766.

To all whom it may concern:

Be it known that I, CLIFFORD C. BRADBURY, a citizen of the United States, residing in Rochester, county of Monroe, and State of New York, have invented a certain new and useful Improvement in Telephone Systems, of which the following is a specification.

My invention relates to telephone systems and particularly to that type of system using automatic or mechanical means at the central office as an aid in establishing the connection between two subscribers' stations.

15 An object of the present invention is to provide a system which is readily convertible from the so-called "call-distributing" to full automatic system and also a system in which the apparatus individual to the line 20 may be used in an exchange provided partially with full automatic equipment and partially with call-distributing equipment.

This feature of the invention becomes particularly desirable when an exchange, 25 equipped for call-distributing, is changed over to an exchange of the full automatic type, since it is desirable to maintain service on all of the lines during the change.

My invention also provides means where- 30 by subscribers who are willing to operate their dials to make full automatic calls may obtain their connection through full automatic means at the central office whereas those subscribers objecting to the use of the 35 impulse sending device at the subscriber's station may obtain their connection through the automatic call-distributing apparatus and a central office operator.

It is customary in manual telephone systems to connect the sleeve or test contacts of the multiple jacks through the coil of a cut-off relay to the ground pole of the central battery and it is also customary in automatic telephone systems to connect the 45 private or test contact of the connector switch multiple through the coil of a cut-off relay with the live or ungrounded pole of the central battery, and briefly stated, my invention comprises the organization of a 50 line circuit whereby the connection of live pole of the central battery upon the sleeve of the multiple jack will actuate the cut-off relay and will connect the ground pole of the central battery with the private contact

of the connector switch multiple of the 55 same line, to establish the busy condition for automatic subscribers, and whereby the connection of the ground pole of the central battery upon the private contact of the automatic multiple will actuate this same 60 cut-off relay and thereby connect the live pole of the central battery to the sleeve contacts of the multiple jacks of this same line to indicate the busy condition of the line to the operators who establish the manual 65 calls.

A further object of my invention is to so organize my line circuit and apparatus as to place the busy conditions before mentioned on both the sleeve contacts of the 70 multiple jacks and the private contacts of the connector multiple when the line apparatus is actuated in initiating a call.

My invention is illustrated in the accompanying drawing, in which all apparatus is 75 shown in its normal or unactuated condition.

Figure 1 represents a manual and an automatic subscriber's station, each connected through similar line circuits and connector switches with the proper apparatus at the 80 central office to complete either the manual or the automatic call as the case may be.

Fig. 2 represents a connector circuit adapted to operate with the lower of the subscribers' stations of Fig. 1, to establish 85 an automatic connection either with the other subscriber's line of Fig. 1 or with another automatic subscriber, and

Fig. 3 represents a cord or manual connecting circuit adapted to operate with the 90 upper subscriber's station and apparatus of Fig. 1 to establish a manual connection between that subscriber and an automatic subscriber, such as the lower of Fig. 1 or any other manual subscriber's line.

It is to be understood that for large exchanges intermediate selector switches may be used between the line switches and the cord and connector circuits here illustrated, suitable switches and circuits for this purpose being illustrated in the co-pending application of Charles E. Hague, Serial Number 556,924, filed April 22, 1910, now Patent No. 1,128,777, granted February 16, 1915.

Referring now to Fig. 1, the automatic 105 subscriber's station 1 is provided with the usual condenser 2 and annunciator 3 permanently connected in a bridge between the

limbs 4 and 5 of the subscriber's line, the limb 5 containing the series contacts 6 and 7 of the subscriber's impulse mechanism 8, and with the transmitter 9 and receiver 10 in a bridge maintained normally open by the contacts of the switch hook 11.

The impulse mechanism 8 comprises a dial 12 having numerals thereon and having finger holds corresponding to the different numerals, by means of which the dial may be rotated in a clockwise direction until the finger strikes the stop 13. During the rotation in this direction the roller 14 is moved about its pivot 15 such that the contact 15 spring 6 is not raised from its point 7, but upon the release of the dial 12 the mechanism is returned to its normal position by means of a spring, not shown in the drawing, and the roller 14 is caused to step over the dial of the star wheel 16, raising the spring 6 and interrupting the circuit between contacts 6 and 7 once for each tooth of the star wheel which passes under the roller.

At the central office line conductor 4 is connected through contacts 20 and 21 of cut-off relay 22 and the coil 23 of relay 24 to the ground pole of battery, and line conductor 5 is connected through contacts 25 and 26 of cut-off relay 22 and the coil 27 of line relay 28 through conductor 29 to the live pole of the main battery A shown on Sheet 3. Cut-off relay 22 is also provided with the normally open contacts 30 and 31 adapted, when the relay is actuated, to extend the limbs 4 and 5 of the telephone line through conductors 32 and 33 to the lever contacts 34 and 35 of relay 24, the lever 35 of this relay being normally connected through contact 36, conductor 37 and the coil 38 of cut-off relay 22 to earth. Conductor 37 is also connected through conductor 40 and the coil 41 of line relay 28 with the normally open contact 42 of that relay. The other contact 43 of relay 28 is connected through conductor 44 with the private wire 45 and with the contact 46 of relay 24 and the contact 48 of relay 22. Contact 46 of relay 24 is adapted to be connected through contact 49 of that relay with the private wire 50 extending to the private segment 51 of line switch 52. The normally closed contact 53 of relay 24 is connected with the lever contact 54 of relay 28 and thence through contact 55, conductor 56 and the coil 57 of relay 22 and conductor 29 to the live pole of battery A. Conductor 56 also connects through the coil 58 of relay 24 and conductor 59 with the contact lever 60 of relay 22, this lever being adapted to connect with contact 48 of that relay before contact 48 breaks from its normal contact 61, this contact 61 being connected through the normally open contacts 62 and 63 of relay 28 and the coil of motor-magnet 64 and interrupter 65 with the live

pole of battery A. The relay 28 is also provided with the grounded contact 68 adapted to connect with the lever contact 54 when the relay is actuated. Conductors 32 and 33 are permanently connected through conductors 69 and 70 with the multiple contacts 71 and 72 of the connector switch shown on Sheet 2 and with the tip and sleeve contacts 73 and 74 of the multiple jacks shown on Sheet 3. Relay 24 also has the normally open contacts 75 and 76 adapted to extend the line conductors 4 and 5 to the talking circuit segments 77 and 78 of the line switch 52.

The line switch 52 which as here conventionally shown comprises a central shaft 80 upon which are mounted the ratchet wheel 81 and the insulated contact wipers 82, 83 and 84, these wipers being adapted to be rotated in a clockwise direction by means of the ratchet pawl 85 and the motor-magnet 64. About the periphery of the line switch a plurality of contacts are held in insulated relation to one another, these contacts being connected with the various trunk circuits 90 accessible to this particular line switch. It will be noted that between the talking circuit segments 77 and 78 there are two blank contacts 87 and 88 and that between segments 77 and 51 there is a single contact 95 and between segments 78 and 51 there is a single contact. It will also be noted that the end contacts 89 and 90 opposite segment 51 are grounded. This arrangement permits the wipers 82 and 83 to pass off of and onto 100 the talking segments 77 and 78 without connecting these segments with earth.

Three of the contacts, 91, 92 and 93 of this line switch, are connected through conductors 94, 95 and 96 to the automatic connector circuit shown on Sheet 2, it being understood that the other contacts of the line switch are connected with other connector circuits similar to that on Sheet 2 and that contacts of a large number of line switches, preferably 110 one hundred, are connected in multiple.

The manual telephone subscriber's station 1' and the apparatus individual thereto shown at the top of Sheet 1 is equipped with apparatus similar to that formerly described 115 with the exception of the automatic sending device at the substation, this latter being omitted from the equipment at substation 1', the corresponding apparatus of this line being designated by like figures with the 120 suffix "1".

Referring now to Fig. 2 it will be seen that the top talking conductor 94 extends to the condenser 100 through conductor 101, normally open contacts 102 and 103 of relay 104, contacts 105 and 106 of ringing relay 107 and conductor 108 to the wiper 109, and that the lower talking conductor 95 extends through condenser 110, conductor 111, normally open contacts 112 and 113 of relay 130

104, contacts 114 and 115 of ringing relay 107 and conductor 116 to the wiper 117. The impulse relay 120 has its coil 121 connected between the talking conductor 94 and 5 the ground pole of the battery A and its coil 122 connected between the talking conductor 95 and the live pole of battery A. This relay controls normally open contacts 123 and 124, contact 123 being connected to 10 ground and the contact 124 being connected to the private conductor 96 and also to the lever contact 125 of the slow acting relay 126. Lever contact 123 normally connects through contact 127 with the open contact 15 182 of relay 126. Relay 120 also has the lever contact 128 normally connecting with contact 129 and adapted upon the actuation of the relay to connect with contact 130. The latter contact is connected through conductor 131 and the coil of relay 126 with the live pole of battery A, and is also connected with the lever contact 132 of relay 133, the inside contact 134 of this relay being connected through its own coil 135 with the live 20 pole of battery A and through contacts 136 and 137 of relay 138 and conductor 139 to the normally open contact 140 of relay 141, the lever contact 142 of relay 141 being connected through conductor 143 with the private wipers 144. Relay 141 also has the grounded contact 145 normally connecting with the lever 142.

The lever contact 128 of relay 120 is connected through conductor 148 and the normal contacts 149 and 150 of relay 104 to earth, conductor 148 being also connected through the coil 151 of relay 104 to earth. The normally closed contact 129 of relay 120 is connected with the normally open contact 40 152 of relay 126, the lever contact 153 of this relay being connected through conductor 154 and normal contacts 155 and 160 of relay 141 and conductor 161 through the coil of the vertical motor-magnet 162 and conductor 163 to the live pole of battery A. The normally open contact 164 of relay 141 is connected through conductor 165 and the coil of the rotary motor-magnet 166 and conductor 163 with the live pole of battery 45 A. The contact 153 of relay 126 is also connected through conductor 154 and conductor 168 through the coil of relay 138 to the live pole of battery A.

The coil of release magnet 170 has one terminal connected through conductor 171 to the brush 172 of interrupter 173 and has its other terminal connected through conductor 174 through normal contacts 175 and 176 of relay 177 and contacts 181 and 180 of relay 126 through conductor 186 to the normally open contact 183 of the vertical off-normal bunch of springs. Contact 176 of relay 177 is also connected to the normally open contact 184 of relay 133, the lever contact 185 of that relay being connected

through conductor 186 to the same contact 183 of the vertical off-normal bunch of springs. The middle spring 188 of the vertical off-normal contacts is connected to earth and the lower spring 189 is connected 70 through conductor 190 and the normal contacts 191 and 192, conductor 193, normal contacts 194 and 195 of relay 138, conductor 196 and the coil of relay 141 to the live pole of battery through conductor 197. The normally open contact 199 of the rotary off-normal set of springs is connected through conductor 200 with the open contact 201 of relay 138 and through contacts 202 and 203 of relay 141 and the coil 204 of relay 104 to the 80 live pole of battery A.

The relay 177 has its coils 206 and 207 connected between talking conductors 101 and 111 and the opposite poles of the main battery A. The normally open contact 208 85 of this relay is connected with the normally closed contact 209 of relay 126. Relay 177 also has the spring contact 210 connected with the normally open contact 211 of relay 104 and connecting through the outside contact 212 and conductor 213 and the coil of ringing relay 107 to the brush 214 of the ringing interrupter 173. The normally open contact 216 of relay 177 is connected through the coil 217 of relay 133 with the 90 live pole of battery A.

The normally closed outside contact 217 of relay 104 is connected through conductor 218 with the inside contact 219 of relay 133, the lever contact 220 of this relay being connected through the secondary winding 221 of the busy buzz induction coil 222 to earth. The primary winding of this induction coil is connected in series with the rapid interrupter 223 and the main battery A. 100

The relay 107 has the normally open contacts 225 and 226 adapted when the relay is actuated to connect the brushes 227 and 228 of ringing generator 229 with the wipers 105 109 and 117, the brush 228 being connected with the live pole of battery A.

With respect to the mechanism of the connector switch shown upon Sheet 2 it is to be understood that the illustration is intended only to show sufficient mechanism to conventionally illustrate an operative device. In this illustration the main shaft 235 carries the ratchet cylinder 236 and the wipers 144, 109 and 117 and has slidably secured to its upper end the rotary ratchet 237, this 115 latter ratchet being keyed to the shaft so that the shaft may be moved longitudinally through the opening in the ratchet wheel but so that the rotary movement of the ratchet 237 and the shaft will be as a unit. The step by step vertical motion of the shaft is accomplished by means of the pawl 238 and the step by step rotary movement is accomplished by the action of the pawl 239, the shaft being held in its various positions 120 125 130

of vertical and rotary movement by the double release dog 240.

Referring now to Fig. 3 of the drawing, it will be seen that conductors 94', 96' and 5 95' of Sheet 1 are extended through conductors 94', 96' and 95' of Sheet 2 to conductors 94', 96' and 95' of Sheet 3, conductors 94' and 95' comprising the answering talking conductors of the cord connecting 10 circuit shown on Sheet 3 and conductor 96' comprising the private conductor for the cord circuit shown on Sheet 3. Talking strand 94' extends through the condenser 245, conductor 246, normal contacts 247 and 15 248 of the operator's listening key 249, normal contacts 250 and 251 of the operator's ringing key to the tip contact 252 of the calling plug and talking conductor 95' extends through condenser 254, conductor 255 20 and normal contacts 256 and 257 of the operator's ringing key to the sleeve contact 258 of the calling plug. The calling plug also has a grounded ring contact 259.

The control relays 260 and 261 are connected in a bridge between talking conductors 94 and 95, this bridge containing the main battery A, while the control relays 262 and 263 are connected in a similar bridge between the talking conductors 246 30 and 255. Relay 260 has the normally open contacts 272 and 273, contact 272 being connected with earth and contact 273 being connected through conductor 267 and the normal contacts 268 and 269 of relay 263 to the 35 common wire 270, which is likewise connected to the similar contacts 269 of one half of the cord circuits appearing at this particular operator's position. Contact 272 of relay 260 also connects through the contacts 274 of key 275 to the private conductor 96', the actuation of key 275 being adapted to interrupt the normal contacts and connect the conductor 96' to earth through contact 276. The control relay 261 has the normally open contacts 280 and 281, the lever 280 being connected through the call signal 282 with the live pole of battery A and the contact 281 being connected through normal contacts 283 and 284 of relay 263 to 45 earth. The normally closed contact 285 of relay 261 is connected with the normally closed contacts 287 and 288 of relay 262 and the calling supervisory lamp 289 with the live pole of battery A. Relay 263 also 50 has the normally open contact 290 which is connected with earth and has the normally open contacts 291 and 292 adapted when closed to complete a shunt about the contacts 247 and 248 of the operator's listening key 60 249.

The operator's communication set comprises the receiver 294 and condenser 295, maintained in a normally open bridge by contacts 296 and 297 of the operator's listening key, this bridge also containing the sec-

ondary winding of the operator's induction coil 298. The operator's listening key also has a pair of auxiliary contacts 299 and 300 adapted upon the actuation of the listening key to complete a circuit through the tertiary winding of the operator's induction coil 298.

The operator's ringing key has the normally open contacts 301 and 302, contact 301 being connected through the alternating current generator 305 to earth, and contact 302 being connected through the non-inductive resistance 304 to the live pole of battery A.

The operation of my system will now be traced as it would occur: first, when a connection is completed from subscriber's station 1 to subscriber's station 1'. In this instance subscriber in charge of substation 1 removes his receiver 10 from switch-hook 11 and thereby completes a circuit from the live pole of battery A through conductor 29, coil 27 of relay 28, contacts 26 and 25 of relay 22, line conductor 5, contacts 6 and 7 of the calling mechanism 8, 90 transmitter 9, receiver 10, switch-hook 11, line conductor 4, contacts 20 and 21 of relay 22 and coil 23 of relay 24 to ground. The current in this path actuates relays 28 and 24 and thus completes a path for current from battery A through the interrupter 65, motor magnet 64, contacts 63 and 62 of relay 28, contacts 61 and 48 of relay 22, contacts 46 and 49 of relay 24, conductor 50, segment 51, private brush 83 and the various grounded contacts of busy trunk lines over which the brush 83 passes until arriving upon contact 93 which is idle and is therefore not grounded.

Upon the private wiper passing onto a non-grounded contact, or if it were normally standing so, a surge of current will flow through conductor 44, contacts 43 and 42 and coil 41 of relay 28, conductor 40 and the coil 38 of relay 22 to ground. The impulse of current through the latter path is not sufficient to actuate the motor magnet 64, but is sufficient to actuate relay 22, changing its contacts to their abnormal condition and at the same time closing a locking circuit for relays 22, 24 and 28, which circuit may be traced from battery 29 through the coil 57 of relay 22, the coil 58 of relay 24, conductor 59, contacts 60 and 48 of relay 22, conductor 44, contacts 43 and 42 and coil 41 of relay 28, conductor 40 and the coil 38 of relay 22 to ground.

The actuation of relay 22 extends the limb 4 of the telephone line through contacts 20 and 30 of relay 22, contacts 34 and 75 of relay 24, segment 77, brush 82, and contact 91 of the line switch to conductor 94, and extends line conductor 5 through contacts 25 and 31 of relay 22, conductor 33, contacts 35 and 76 of relay 24, segment 78, 125 130

brush 84 and contact 92 of the line switch to conductor 95. A path for current is therefore immediately completed from the battery conductor 29, Sheet 2, through the 5 coil 122 of relay 120, conductor 95, contact 92, brush 84, segment 78, contacts 76 and 35 of relay 24, conductor 33, contacts 31 and 25 of relay 22, line conductor 5, contacts 6 and 7 of the subscribers' interrupter, trans- 10 mitter 9, receiver 10, switch-hook 11, line conductor 4, contacts 20 and 30 of relay 22, conductor 32, contacts 34 and 75 of relay 24, segment 77, brush 82, contact 91, conductor 94 and coil 121 of relay 120 to ground. The 15 current in this path actuates relay 120 which connects the private conductor 96 through contacts 124 and 123 of relay 120 to earth. Thereupon a new circuit is completed from the battery conductor 29, Sheet 1, through 20 the coil 57 of relay 22, coil 58 of relay 24, conductor 59, contacts 60 and 48 of relay 22, contacts 46 and 49 of relay 24, conductor 50, segment 51, brush 83, contact 93, conductor 96, and contacts 124 and 123 to ground. 25 The current in this path maintains the actuation of relays 22 and 24 and the ground upon conductor 50 shunts the coil 41 of line relay 28 so that that relay now returns to its normal condition. This portion of the op- 30 eration has occurred almost instantly and before the subscriber has had an opportunity to move his dial 12 to call the desired subscriber.

The system here shown is illustrated with- 35 out an intermediate or selector switch, but it is to be understood that my invention is applicable to systems of any size no matter what number of selector switches are applied. In the present system however the 40 calling subscriber would operate his dial but twice to receive the desired connection. The subscriber therefore places his finger in the finger hold opposite the first figure in the number of the desired subscriber and rotates 45 the dial 12 until the movement is interrupted by contact between the finger and the stop 13. During this rotation the roller 14 swings to the right about its pivot 15 and therefore does not raise the spring 6 off of 50 its contact 7. Upon the return of the dial 12 however the roller 14 steps from one tooth to another on the star wheel 16 and therefore interrupts the circuit between contacts 6 and 7 a number of times equal to the first 55 figure in the desired subscriber's number.

The original actuation of relay 120, Fig. 2, completed the circuit from the battery wire 29 through the coil of slow acting relay 126, conductor 131, contacts 130 and 128 of 60 relay 120, conductor 148, and contacts 149 and 150 of relay 104 to ground. The current in this path caused the actuation of the slow acting relay 126 moving its contacts to their abnormal positions.

65 The interruption of the current through

the coils of relay 120, caused by the rotation of the dial at the subscriber's station, causes a similar periodic deenergization of relay 120, but the relay 126, being made slow acting by means of a copper shell about its core, remains in its actuated condition during the periodic interruption of the current through its coil due to the release of the relay 120. Therefore at each release of the 70 armature 128 of relay 120 a circuit is closed from the battery conductor 29 through conductor 163, the coil of the vertical motor-magnet 162, conductor 161, contacts 160 and 155 of relay 141, conductor 154, the now closed contacts 153 and 152 of relay 126, 75 contacts 129 and 128 of relay 120, conductor 148 and contacts 149 and 150 of relay 104 to earth. The current in this path actuates the vertical motor-magnet, stepping the shaft 225 up step by step to a position 80 corresponding to the number of impulses sent over the line by the rotation of the dial at the subscriber's station. At the same time the slow acting relay 138 is actuated from the battery wire 29 through its coil, conductors 168 and 154, contacts 153 and 152 of relay 126, contacts 129 and 128 of relay 120, conductor 148 and contacts 149 and 150 of relay 104. Although relay 120 does not 85 remain continuously actuated, the ground connection will still be maintained on the private conductor 96 through a path which may be traced from ground through the back contacts 123 and 127 of relay 120, contacts 182 and 180 of relay 126, contacts 185 and 147 of relay 133, contacts 146 and 125 of relay 126 to conductor 96. At the termination of the first set of impulses sent from the calling subscriber's station the relay 138 falls back to its normal condition 90 and thereupon completes a circuit from the battery conductor 29 through conductor 197, coil of relay 141, conductor 196, contacts 195 and 194, conductor 193, normally closed contacts 192 and 191 of the rotary off-normal set of springs, conductor 190 and the now closed contacts 189 and 188 of the vertical off-normal springs to ground. The current in this path actuates relay 141 95 changing its contacts to their abnormal positions. In the meantime the calling subscriber has moved his dial to a position corresponding to the last figure in the desired number and now releases the dial, sending a corresponding number of impulses over the 100 telephone line. Relay 120 is again periodically released which now closes a circuit from the battery conductor 29 through conductor 163, the coil of the rotary motor-magnet 166, contacts 164 and 155 of the now actuated relay 141, conductor 154, contacts 153 and 152 of relay 126, contacts 129 and 128 of relay 120, conductor 148, and contacts 149 and 150 of relay 104 to earth. The 105 current in this path moves the shaft 235 in 110

a rotary direction step by step until the wipers 117, 109 and 144 have arrived upon the talking and private contacts of the desired line. As before, the relay 138 is actuated during the time the impulses are being sent over the line and the circuit of the slow acting relay 141 is therefore immediately severed at contacts 194 and 195 of relay 138. However the relay 141 is not released 5 since a new circuit is immediately established from battery conductor 29 through conductor 197, coil of relay 141, conductor 196, contacts 195 and 201 of relay 138, conductor 200, the now closed contacts 199 and 15 191 of the rotary off-normal set of springs, conductor 190 and contacts 189 and 188 of the vertical off-normal set of springs to ground. At the termination of this last set of impulses sent from the subscriber's station, relay 120 remains actuated and relay 20 138 therefore returns to its normal position. The severing of its contacts 195 and 201 now 25 interrupts the circuit of relay 141 since conductor 193 is now open at the contacts of the rotary off-normal springs.

When the relay 141 returns to its normal position a ground connection is established through its contacts 145 and 142 and conductor 143 upon the private wiper 144 and 30 private conductor 45' thence through contacts 46' and 53' of relay 24', contacts 54' and 55' of relay 28' and the coil 57' of cut-off relay 22' to the live pole of battery A. The current in this path actuates the cut-off relay 22' which frees the line from its 35 normal connections with the line relay. The ground connection with private conductor 45' establishes the busy condition upon this conductor for purposes hereinafter explained. The release of relay 141 establishes a path for current from the battery conductor 29 through conductor 197, the coil 204 of relay 104, contacts 203 and 202 of relay 141, conductor 200, contacts 199 40 and 191 of the rotary off-normal set of springs, conductor 190 and contacts 189 and 188 of the vertical off-normal set of springs to ground. The current in this path actuates relay 104, extending the talking circuit 45 through contacts 102 and 103 and contacts 112 and 113 to the outside contacts 105 and 114 of ringing relay 107. At the same time the actuation of relay 104 closes its contacts 211 and 150 which complete the circuit of 50 the ringing relay 107 from battery conductor 29 through interrupter 173, brush 214, the coil of ringing relay 107, conductor 213, contacts 212 and 210 of relay 177 and contacts 211 and 150 of relay 104 to ground. 55 The current in this path causes the periodic actuation and release of the ringing relay 107. Whenever this relay is actuated its contacts 106 and 115 are connected with the inside contacts 225 and 226 which extend to 60 the brushes 227 and 228 of the alternating

current ringing generator 229, thus periodically sending ringing current over conductors 108 and 116 and through the brushes 109 and 117 and contacts 71 and 72 over the desired telephone line to the substation. 70

Before the ringing current is applied however the release of relay 141 has placed a ground connection through its contacts 145 and 142, conductor 143, brushes 144, private conductor 45', contacts 46' and 53' of relay 24', contacts 54' and 55' of relay 28', conductor 56' and the coil 27' of cut-off relay 22' to the battery conductor 29. The current in this path has actuated the cut-off relay 22' which extends the bank contacts 80 71' and 72' of the connector switch directly through conductors 70' and 69', contacts 30' and 20' and 31' and 25' of cut-off relay 22' and line conductors 4' and 5' to the condenser 2' and annunciator 3' at the desired subscriber's station. 85

When the desired subscriber answers his call by the removal of his receiver from the switch-hook a path for current is completed, during the interrupted period of the ring- 90 ing relay 107, from battery conductor 29 through the coil 207 of relay 177, conductor 111, contacts 112 and 113 of relay 104, contacts 114 and 115 of relay 107, conductor 116, brush 117, contacts 72', conductor 69', 95 conductor 32', contacts 30' and 20' of relay 22', conductor 4', switch-hook 11', receiver 10', transmitter 9', line conductor 5', contacts 25', and 31' of relay 22', conductors 33' and 70', contact 71', brush 109, conductor 100 108, contacts 106 and 105 of relay 107, contacts 103 and 102 or relay 104, conductor 101 and the coil 206 of relay 177 to ground. The current in this path actuates relay 177. The actuation of this relay interrupts the circuit of the ringing relay 107 at contacts 212 and 210 of relay 177 and closes a circuit from battery conductor 29 through the coil 217 of relay 133, contacts 216 and 210 of relay 177 and contacts 211 and 150 of relay 104 105 to ground. The current in this latter path actuates relay 133. The actuation of relay 133 closes a locking circuit for that relay from battery conductor 29 through its coil 135, contacts 134 and 132 of relay 133, contacts 130 and 128 of relay 120, conductor 148 and the coil 151 of relay 104 to ground. 110 This locking circuit also being a locking circuit for the relay 104.

The calling and called subscribers are now 120 in conversation. The current for supplying the energy to the transmitter of the calling telephone line is fed through coils 121 and 122 of relay 120 and the current for supplying the energy for the transmitter of the 125 called telephone line is supplied through the coils 206 and 207 of relay 177. The two lines are electrically isolated by the condensers 100 and 110 interposed in the talking circuit. The only other relays associated with 130

the connecting circuit, which are now maintained actuated, are relays 126, 104 and 135, the relays 141, 138 and 107 being now in their normal conditions.

- 5 If now the called subscriber is the first to replace his receiver upon the switch-hook the circuit is interrupted through the coils 206 and 207 of the bridged relay 177. This relay therefore resumes its normal position and in so doing completes a circuit from battery wire 29 through interrupter 173, brush 172, conductor 171, coil of release magnet 170, conductor 174, contacts 175 and 176 of relay 177, contacts 184 and 185 of the 10 now actuated relay 133, conductor 186 and contacts 183 and 188 of the vertical off-normal set of springs to ground. The current in this path actuates the release magnet 170 which, through its action upon the double release dog 240, permits the shaft 235 to return to its normal position both as to rotary and vertical displacement. Upon the return of the shaft 235 to its normal position, the circuit through the release magnet 15 is again interrupted at contacts 183 and 188 of the vertical off-normal springs, these springs being now separated. When the calling subscriber replaces his telephone upon its hook the circuit through the coils 30 121 and 122 of relay 120 is severed. Relay 120 therefore returns to its normal condition and upon so doing interrupts the circuits through the coil of relay 126 at contacts 130 and 128 and at the same time 35 interrupts the locking circuits of relays 133 and 104. The release of relays 120 and 126 removes the ground connection from private conductor 96 thus allowing the line circuit relays to resume their normal positions. Thus all of the relays associated with the line and connecting circuits are returned to their normal conditions and the circuits 40 may be used again for completing another call.
- 45 It frequently occurs that the calling subscriber replaces his receiver upon the switch-hook before the called subscriber replaces his. In this instance, in order to prevent the called subscriber from initiating a new call by having his receiver off the hook at the time the calling subscriber disconnects, provision is made whereby the connecting switch will not be disconnected, but only the apparatus carrying the connection from the calling subscriber to the connector switch will be released. Thus when the calling subscriber replaces his receiver before the called subscriber has replaced his the relay 120 is released whereas the relay 177 remains in its actuated condition. The release of relay 120 interrupts the circuit of relay 126 allowing that relay to return to its normal condition. The return of relay 120 to its normal condition removes 50 the ground connection from private conductor 96 through contacts 124 and 123 of that relay, but upon the return of relay 126 to its normal condition the ground connection is reestablished upon private conductor 96 through contacts 125 and 209 of relay 126, contacts 208 and 176 of the actuated relay 177, contacts 184 and 185 of relay 133, conductor 186 and contacts 183 and 188 of the vertical off-normal springs. In this manner, although the apparatus used in 55 completing the connection between the calling subscriber's line and the connector circuit is released, the ground is replaced upon the private conductor 96 so that the connector circuit will not again be selected. When 60 the called subscriber now replaces his receiver upon the hook the circuit is interrupted through coils 206 and 207 of relay 177, permitting that relay to return to its normal condition. Upon so doing a circuit 65 is established as formerly described through the release magnet 170 which actuates that magnet to return the connector switch to its normal condition.
- 70 It frequently occurs that a desired line 90 is busy, and therefore means are provided to notify the calling subscriber of the busy condition of the desired line. The various operations for completing a connection will in this case be carried out the same as previously described until the last impulse has been sent from the calling subscriber's station and the wipers of the connector switch arrive upon the contacts of the desired line. If this line is busy either as a 95 calling or a called telephone line, its private contact 45' is grounded and therefore when the impulses from the subscriber's dial have ceased and the relay 138 has resumed its 100 normal condition, a circuit is established 105 from the ground pole of battery at brushes 144 through conductor 143, contacts 142 and 140 of the now actuated relay 141, conductor 139, contacts 137 and 136 of relay 138, and the coil 135 of relay 133 to the battery 110 conductor 29. The current in this path actuates relay 133. The actuation of this relay closes its contacts 184 and 185, thus completing a circuit from battery conductor 29 through interrupter 173, brush 172, conductor 171, the coil of the release magnet 170, conductor 174, contacts 175 and 176 of relay 177, contacts 184 and 185 of relay 133, conductor 186 and contacts 183 and 188 of the vertical off-normal springs. The 115 current in this path causes the actuation of the release magnet 170 and returns the switch to its normal condition which again 120 interrupts the circuit of the release magnet. The actuation of relay 133 also closes its 125 contacts 220 and 219 completing a circuit from the busy tone producer 222 through the coil 221, contacts 220 and 219 of relay 133, conductor 218, contacts 217 and 112 of relay 104, conductor 111, condenser 110 and 130

over the path previously described through the receiver at the calling subscriber's station and back to earth through the coils 121 and 206 of relays 120 and 177. This notifies 5 the calling subscriber that the desired line is busy and he therefore replaces his receiver upon the switch-hook and releases the apparatus in the manner previously described.

- 10 When substation 1' desires a connection through the central office with either an automatic subscriber or another manual subscriber, the receiver 10' is removed from the switch-hook in the usual way, thus completing a circuit from battery conductor 29 through the coil 27' of line relay 28', contacts 26' and 31' of relay 22', line conductor 5', transmitter 9', receiver 10', switch-hook 11' line conductor 4', contacts 20' and 21' of cut-off relay 22' and coil 23' of relay 24' to earth. The current in this path actuates relays 28' and 24'. The actuation of relay 28' completes a circuit from the battery conductor 29 through interrupter 25 65, the coil of motor-magnet 64', contacts 63' and 62' of relay 28', contacts 61' and 48' of relay 22', contacts 46' and 49' of relay 23', conductor 50', segment 51' and the various busy or grounded contacts of the 30 line switch to earth, thus moving the spider of the line switch step by step until the private wiper 83' is moved onto a non-grounded contact 93'. When a non-grounded contact is reached, or if the private 35 wiper normally stood upon a non-grounded contact there is no movement and current now flows from the battery conductor 29, through interrupter 65, coil of motor-magnet 64', contacts 63' and 62' 40 of relay 28', contacts 61' and 48' of relay 22', conductor 44', contacts 43' and 42' and coil 41' of relay 28', conductor 40' and the coil 38' of relay 22' to ground. The current in this path actuates relay 22' 45 closing a locking circuit for all three of the relays which may be traced from battery conductor 29 through the coil 57' of relay 22', the coil 58' of relay 24', conductor 59', contacts 60' and 48' of relay 22', contacts 43' and 42' and coil 41' of relay 28', conductor 40' and the winding 38' of relay 22' to ground.
- The relays 22' and 24' now being actuated, line conductors 4' and 5' are extended 55 through conductors 32' and 33' and the contacts 75' and 76' to the segments 77' and 78' of the line switch and thence through wipers 82' and 84' and contacts 91' and 92' to the talking conductors 94' and 95' which 60 extend to the cord circuit shown upon Sheet 3 of the drawing. A circuit is therefore immediately completed from the live pole of battery A, Sheet 3, through the coil of relay 261, conductor 95', contact 92' of the 65 line switch, Sheet 1, brush 84', segment 78',

contacts 76' and 35' of relay 24', conductor 33', contacts 31' and 25' of relay 22', conductor 5', transmitter 9', receiver 10', switch-hook 11', line conductor 4', contacts 20' and 30' of relay 22', conductor 32', contacts 70 34' and 75' of relay 24', segment 77' brush 82', contact 91', conductor 94' and the coil of relay 260 to the ground pole of battery A. The current in this path actuates relays 260 and 261. The actuation of relay 260 75 immediately connects the ground pole of battery A through its contacts 272 and 273 and the contacts of the busy key 275 with the private conductor 96' which extends to contact 93' of the line switch and thence 80 through brush 83' segment 51', conductor 50', contacts 49' and 46' of relay 24', contacts 48' and 60' of relay 22', conductor 59', coil 58' of relay 24' and coil 57' of relay 22' to the battery conductor 29. The current in this path maintains the actuation of relays 22' and 24', but the ground upon the private conductor places a shunt about the coil 41' of relay 28' thus allowing that relay to return to its normal condition. 90

The actuation of relay 261 completes the circuit of the call lamp 282 from the live pole of battery A through the lamp, contacts 280 and 281 of relay 261, and contacts 283 and 284 of relay 263 to ground. The 95 operator, observing the display of the call lamp 282, actuates her listening key 249 and thus places her receiver 294 and the condenser 295 in a bridge between the talking conductors 246 and 255. The operator 100 now obtains the number of the desired subscriber's telephone and tests the sleeve or test contact of the multiple jack of said line by touching the tip 252 of her calling plug to the sleeve of the jack of the desired line. 105

If the line is busy either as a calling or a called line the sleeve contacts of all of its multiple jacks will be maintained at a potential higher than that of ground and current will therefore flow from the sleeve of the 110 tested jack over the tip 252, contacts 251 and 250 of the operator's ringing key, auxiliary contacts 299 and 300 and the tertiary winding of the operator's induction coil to ground. The current in this path causes 115 inductive disturbance in the secondary winding of the operator's induction coil which is heard by the operator and thus indicates in the usual way that the line is busy.

Assuming however that the line is found 120 idle the operator inserts her calling plug completely into the jack of the desired line and causes the tip ring and sleeve contacts 252, 259 and 258 to electrically connect with the tip ring and sleeve contacts 73, 79 and 125 74 of the desired line, for convenience assuming the desired line to be that of substation 1, though it may be another manual telephone line.

The operator now actuates her ringing 130

key causing its contacts 251 and 257 to register with contacts 301 and 302. A circuit is thus established from battery conductor 29 through the non-inductive resistance 304, contacts 302 and 257 of the ringing key, sleeve contacts 258 and 74 of the plug and jack, conductor 70, contacts 35 and 36 of relay 24, conductor 40, and to coil 38 of cut-off relay 22 to ground. The current in this 5 path actuates relay 22. A circuit is now completed from the ringing generator 305, Sheet 3, through contacts 301 and 251 of the ringing key, tip contacts 252 and 73 of the plug and jack, conductor 69, conductor 32, 10 contacts 30 and 20 of the now actuated relay 22, line conductor 4, annunciator 3, condenser 2, contacts 7 and 6 of the subscriber's impulse mechanism, line conductor 5, contacts 25 and 31 of cut-off relay 22, conductor 15 tors 33 and 70, sleeve contacts 74 and 258 of the jack and plug, contacts 257 and 302 of the operator's ringing key and the non-inductive resistance 304 to the battery conductor 29. The current in this path being 20 alternating in character sounds the annunciator 3 at the station of the desired subscriber.

The operator now releases her ringing key and thereby completes a circuit from the 30 live pole of battery A through the coil of relay 263, conductor 255, contacts 256 and 257 of the operator's ringing key, sleeve contacts 258 and 74 of the plug and jack, conductor 70, contacts 35 and 36 of relay 35 24, conductor 37 and the coil 38 of cut-off relay 22 to ground. The current in this path maintains the actuation of cut-off relay 22 and actuates relay 263. The actuation of relay 263 interrupts the circuit of 40 call lamp 282 at contacts 283 and 284 and completes the circuit of the calling lamp 289 at contacts 284 and 286. The actuation of relay 263 also disconnects the private conductor 96' from the common point 270 and 45 connects it to ground through contacts 268 and 290. It may here be noted that the actuation of relay 260 not only grounded the private conductor 96', but also through conductor 267 and contacts 268 and 269 of relay 263 grounded the common conductor 270. This common conductor extends preferably to one half of the cord circuits appearing at a single operator's position and therefore during the time that relay 260 50 is actuated and before relay 263 is actuated, all of the private wires which are normally connected to the conductor 270 are grounded, which prevents other calls from being connected with the cord circuits of this particular group while the operator is busy answering one call. The actuation of relay 263 also closes contacts 291 and 292 which complete a shunt about the contacts 247 and 248 of the operator's listening key.

65 When the called subscriber answers his

call a path for current is completed from the live pole of battery A through the coil of relay 263, conductor 255, contacts 256 and 257 of the operator's ringing key, sleeve contacts 258 and 74 of the plug and jack, conductors 70 and 33, contacts 31 and 25 of cut-off relay 22, line conductor 5, contacts 6 and 7 of the subscriber's interrupter, transmitter 9, receiver 10, switch-hook 11, line conductor 4, contacts 20 and 30 of relay 22, 70 conductors 32 and 69, tip contacts 73 and 252 of the jack and plug, contacts 251 and 250 of the operator's ringing key, contacts 248 and 247 and contacts 292 and 291 in parallel, conductor 246 and the coil of relay 262 to the ground pole of battery A. The current in this path actuates relay 262 separating its contacts 287 and 288 and thus effacing the calling lamp 289. The calling and called subscribers are now in conversation and all signals are effaced at the central office. The current for the transmitter of the calling line is fed through the coils of relays 260 and 261 and the current for the transmitter of the called line is fed 80 through the coils of relays 262 and 263.

When both the calling and called subscribers replace their receivers upon their respective switch-hooks, the circuits are interrupted through relays 260 and 261 and 85 through relay 262. The release of relay 260 does not remove the ground connection from the private conductor 96' for the reason that this conductor is grounded through conductor 267 and contacts 268 and 290 of 90 relay 263. The release of relay 261 now completes the circuit of the call lamp 282 from the live pole of battery A through the lamp, contacts 280 and 285 of relay 261 and contacts 286 and 284 of relay 263 to 100 ground. The release of relay 262 completes the circuit of the calling lamp 289 from the live pole of battery A through the lamp, contacts 288 and 287 of relay 262 and contacts 286 and 284 of relay 263 to ground. 105 The display of signals 282 and 289 indicates to the operator that the subscribers have both replaced their receivers upon their respective switch-hooks and she then removes her calling plug from the jack which 110 severs the circuit of relay 263. The release of relay 263 removes the ground connection from the private conductor 96' allowing the relays 24' and 22' to return to 115 their normal conditions and also interrupts the circuits of the lamps 282 and 289. The removal of the calling plug also interrupts the circuit through the coil 38 of relay 22, thus allowing that relay to return to normal. The apparatus has now all returned 120 to normal and is in condition for another 125 call.

It will be seen that the line circuit of my invention, here illustrated, may be operated either with a full automatic telephone sys- 130

tem or a call-distributing telephone system, and that I have provided a system in which subscribers may be provided with either call-distributing or full automatic service 5 according to their desires.

The private contacts of the automatic connector switch multiple are carried to the ring contacts 79 of the multiple jacks and the ring contacts 259 of all of the cord circuits are grounded so that the insertion of a plug into one of the multiple jacks places the busy condition upon the private contacts of this line throughout the automatic connector switch multiple. Likewise when 10 a connection is established through the automatic connector switch with any line, the sleeve contacts of all of the multiple jacks are raised to a potential above ground through contacts 35 and 36 of relay 24. In 15 this manner an automatic and a manual connection will not be established with a single line at the same time. While I have shown and described my invention with reference to a particular embodiment it is to be understood that many alterations may be made 20 therefrom without departing from the spirit 25 or scope of my invention.

What I claim is:—

1. In a telephone system, the combination 30 with manual and automatic telephone lines, of connecting means at the central office for establishing either manual or automatic connections with either of said lines, the establishment of an automatic connection with 35 either of said lines being adapted to place battery potential upon the test contacts of the manual connecting means and ground potential upon the test contacts of the automatic connecting means to indicate that the 40 line is busy both for automatic and manual connections, and the establishment of a manual connection with either of said lines being adapted to indicate that the line is busy both for manual and automatic connections.

2. In a telephone system, the combination 45 with a telephone line, of multiple jacks and multiple automatic connector contacts for said line, a cut-off relay for the line and means to actuate said cut-off relay either by 50 the establishment of a manual connection with said multiple jacks or by the establishment of an automatic connection with said multiple automatic connector contacts, and means to place battery potential upon the 55 test contacts of the multiple jacks and ground potential upon the automatic connector contacts by the establishment of either of said connections.

3. In a telephone system, the combination 60 with a telephone line, of multiple jacks and multiple automatic connector contacts for said line, a cord circuit and a connector switch, a cut-off relay for the line, the establishment of a connection between either the cord circuit or the automatic connector switch and

said line, being adapted to connect the grounded pole of battery with the private contacts of the connector switch multiple and the non-grounded pole of battery with the test contacts of the multiple jacks. 70

4. In a telephone system, the combination with a telephone line, of a cut-off relay for the line, a central source of current, contacts for establishing a connection with said line, a pair of conductors extending from said 75 contacts to the line circuit, a cut-off relay for the line having a coil normally connected between one of said conductors and the ground pole of the main battery, a third conductor, said cut-off relay having a coil connected between the live pole of the main battery and said third conductor. 80

5. In a telephone system, the combination with a telephone line, of multiple jacks having a pair of conductors for establishing a 85 connection with said line, a cut-off relay for the line having a coil connected to one of said conductors, an automatic connector switch multiple having said pair of wires and a third wire for establishing a connection 90 with said line, said cut-off relay having a coil connected with said third wire.

6. In a telephone system, the combination with a telephone line, of a cut-off relay for the line, a pair of conductors over which a 95 conversational circuit is adapted to be completed when said line is called, and a third conductor independent of the talking circuit, said cut-off relay being adapted to be actuated either over one of said talking conductors or over said third conductor. 100

7. In a telephone system, the combination with calling and called subscribers' lines, of a selector switch and a connector switch serially connected to establish a talking circuit 105 between said subscribers' lines, multiple test or guard contacts between said selector and connector switches, a release circuit including one of said contacts and means responsive to the interruption of current in the calling 110 subscriber's line for momentarily removing and replacing the guard potential of said multiple test contacts, and release mechanism for said selector switch actuated by the momentary removal of the guard or test potential. 115

8. In a telephone system, the combination with a telephone line, multiple jacks and multiple automatic switch contacts for said line, a central battery, a cut-off relay for the line adapted to be actuated under two 120 conditions, first by the connection of one pole of said battery to multiple jack contacts of said line and second by the connection of the other pole of said battery to multiple automatic connector contacts of said line. 125

9. In a telephone system, the combination with a connector switch, of a calling and a called subscriber's line adapted to be connected through said switch, selecting apparatus for establishing the connection between 130

a calling line and an idle connector switch, a private conductor extending between the selective apparatus and the connector switch, a relay in said conductor energized during 5 conversation, said conductor being charged from the connector switch with busy potential during conversation to prevent other selector switches from connecting with the busy connector switch, the deenergization of 10 said relay serving to release the selecting apparatus when the calling subscriber replaces his receiver upon its hook, and means for maintaining the busy condition on the private contacts extending to said connector 15 switch to prevent other selector switches from connecting therewith before the called subscriber has replaced his receiver upon its hook.

10. In a telephone system, the combination 20 with calling and called subscribers' lines, of a selector switch and a connector switch serially connected to establish a talking circuit between said subscribers' lines, multiple test or guard contacts between said selector and 25 connector switches, a release circuit including one of said contacts and means responsive to the interruption of current in the calling subscriber's line for momentarily removing and replacing the guard potential of 30 said multiple test contacts, release mechanism for said selector switch actuated by the momentary removal of the guard or test potential, and means controlled by the interruption of the called subscriber's circuit for 35 thereafter continuously removing the guard potential from said multiple contacts.

11. In a telephone system, the combination 40 with a calling and a called telephone line, of selector and connector switches connected in tandem for establishing a talking circuit between said telephone lines, a private conductor extending between said switches and charged with busy potential to prevent interference with the established talking circuit, 45 an electro-magnet for the selector switch maintained in actuated condition over said private conductor, and means associated with the connector switch for interrupting the circuit of said electromagnet to release said 50 selector switch, and means to reestablish the busy potential upon the interrupted portion of the private conductor extending to the connector switch to prevent said switch from being again selected.

55 12. In a telephone system, the combination 60 with a pair of telephone lines, of a plurality of automatic switches connected in series between the calling and the called telephone line, a private conductor extending from one switch to its adjacent switch in the series, test contacts for the latter switch in electrical connection with said private conductor, a release relay for the one of said switches nearest the calling line 65 continuously actuated during the use of said

switches by current flowing over the private conductor extending from said switch to the switch next in series toward the called subscriber's line, and means for interrupting said private conductor to bring about the 70 release of said first switch, and means operating immediately thereafter to restore busy potential on the multiple test contacts of the second switch.

13. In a telephone system, the combination 75 with an established talking circuit, of a pair of serially connected switches having contacts included in said talking circuit, of a test and release trunk extending between said switches and including multiple test 80 contacts, means under the control of the calling subscriber to release one of said switches and prevent the selection of the other of said switches, and means under the control of the called subscriber for releasing the other 85 of said switches without freeing either of said switches for use, and means thereafter under the control of the calling subscriber for releasing one of said switches and freeing the other for use. 90

14. In a telephone system, the combination 95 with a connector switch, of a test wiper therefor and means to move said wiper into engagement with various stationary contacts, a pair of electromagnets controlling contacts serially included in circuit with said test wiper, a test relay adapted to be connected with said test wiper by the release of one of said electromagnets and again disconnected therefrom by the release of the 100 second electromagnet, and a source of busy tone current connected with the conductors of the connector switch through the actuation of said test relay.

15. In a telephone system, the combination 105 with a connector switch, of a test wiper therefor and means to move said wiper into engagement with various stationary contacts, a pair of electromagnets controlling contacts serially included in circuit with 110 said test wiper, a test relay adapted to be connected with said test wiper by the release of one of said electromagnets and again disconnected therefrom by the release of the second electromagnet, and means responsive 115 to the release of said second electromagnet for applying busy potential to the test wiper.

16. In a telephone system, the combination 120 with a calling subscriber's line and a plurality of subscribers' lines to be called, of a test contact for each subscriber's line and means to apply busy potential thereto when the subscriber's line is in conversation, a connector switch and a movable test wiper 125 therefor adapted to engage the test contact of a line when a connection is desired with said line, a pair of electromagnets for the connector switch and contacts controlled thereby and a circuit for the first completed 130

by the actuation of the second, means to interrupt the circuit of the second after the arrival of the movable test wiper upon the test contact of a desired line, a test relay 5 and a circuit therefor extending through contacts closed by the release of the second electromagnet and contacts to be opened by the release of the first electromagnet to said test wiper, whereby, if the called subscriber's 10 line is busy and therefore has busy potential upon its test contact current will flow through the coil of the test relay during the interval after the release of the second electromagnet and before the release of the first 15 electromagnet.

17. In a telephone system, a line, a non-numerical trunking switch individual thereto, trunk lines for talking purposes leading therefrom, said switch having line wipers 20 always in electrical engagement with some one of said trunk lines, which connected trunk line is always the one last employed by said switch for extending a call, normally open connections between said line 25 and line wipers, a relay, means for energizing said relay over the line circuit, and means operated upon the energization of said relay to close said normally open connections.

18. In a telephone system, a line, a non-numerical trunking switch, trunk lines for talking purposes leading therefrom, said switch having line wipers always in electrical engagement with some one of said trunk lines, which connected trunk line is 30 always the one last employed by said switch for extending a call, said switch having a step-by-step actuated shaft that always rotates in the same direction, normally open connections between said line and line 35 wipers, a relay, means for energizing said relay over the line circuit, and means operated upon the energization of said relay to close said normally open connections.

19. In a telephone system, an automatic 45 trunking switch, trunk lines for talking purposes leading therefrom, terminals for said trunk lines, said switch having line wipers always in electrical engagement with the terminals of some one of said trunk lines, which 50 connected trunk line is always the one last employed by said switch for extending a call, a telephone line to which said switch is individual, a normally deenergized relay controlling, on energization, the connection 55 between the said telephone line and switch, and means whereby said trunking switch will extend a connection over said connected trunk if the same is idle.

20. In a telephone system, a line, a non- 60 numerical trunking switch, trunk lines for talking purposes leading therefrom, said switch having line wipers always in electrical engagement with some one of said trunk lines, which connected trunk line is always 65 the one last employed by said switch for ex-

tending a call, means for controlling said switch over the two sides of a metallic line circuit in series, normally open connections between said line and line wipers, a relay, means for energizing said relay over the line 70 circuit, and means operated upon the energization of said relay to close said normally open connections.

21. In a telephone system, a non-numerical trunking switch, trunk lines for talking purposes leading therefrom, said switch having line wipers always in electrical engagement with some one of said trunk lines, which connected trunk line is always the one last employed by said switch for extending a call, 75 an automatic selector switch at the other end of said trunk lines, and means for controlling said switches over two sides of a metallic line circuit in series.

22. In a telephone system, an automatic 80 trunking switch, trunk lines for talking purposes leading therefrom, terminals for said trunk lines, said switch having line wipers always in electrical engagement with the terminals of some one of said trunk lines, which 85 connected trunk line is always the one last employed by said switch for extending a call, an automatic selector switch at the other end of each of said trunk lines, and means for controlling said switches over two sides of 90 a metallic line circuit in series.

23. In a telephone system, a non-numerical trunking switch, trunk lines for talking purposes leading therefrom, said switch having line wipers always in electrical engagement 100 with some one of said trunk lines, which connected trunk is always the one last employed by said switch for extending a call, other switches for using said trunk lines in extending calls, means allotted to each trunk line 105 for causing said first-mentioned switch to automatically select another trunk line if the one which it used last is busy when it again responds to a call, normally open connections between said line and line wipers, a relay, 110 means for energizing said relay over the line circuit, and means operated upon the energization of said relay to close said normally open connections.

24. In a telephone system, an automatic 115 trunking switch, trunk lines for talking purposes leading therefrom, terminals for said trunk lines, said switch having line wipers always in electrical engagement with the terminals of some one of said trunk lines, which 120 connected trunk line is always the one last employed by said switch for extending a call, other switches for using said trunk lines in extending calls, means allotted to each trunk line for causing said first-mentioned switch 125 to automatically select another trunk line if the one which it used last is busy when it again responds to a call, normally open connections between said line and line wipers, a relay, means for energizing said relay over 130

the line circuit, and means operated upon the energization of said relay to close said normally open connections.

25. In a telephone system, a line, a non-numerical trunking switch, trunk lines for talking purposes leading therefrom, said switch having line wipers always in electrical connection with one of said trunk lines, which connected trunk line is always the last one employed by said switch for extending a call, normally open connections between said line and line wipers, and a double-wound relay for controlling, upon energization, said normally open connections.
- 10 26. In a telephone system, a line, a non-numerical trunking switch, trunk lines for talking purposes leading therefrom, said switch having line wipers always in electrical

connection with one of said trunk lines, which connected trunk line is always the last one employed by said switch for extending a call, normally open connections between said line and line wipers, a double-wound relay for controlling said normally open connections, means for energizing said relay to close said connections when connection is made with an idle trunk, and means for preventing said relay from energizing when said wipers contact with a busy trunk.

Signed by me at Rochester, county of Monroe, and State of New York, in the presence of two witnesses.

CLIFFORD C. BRADBURY.

Witnesses:

FRANZ J. DOMMERQUE,
CHARLES E. HAGUE.
